UNITED STATES PATENT OFFICE.

ELIZABETH M. FOREHAND, OF KOKOMO, INDIANA.

SKIRT-LIFTER.

SPECIFICATION forming part of Letters Patent No. 683,597, dated October 1, 1901.

Application filed May 21, 1901. Serial No. 61,253. (No model.)

To all whom it may concern:

Be it known that I, ELIZABETH M. FOREHAND, a citizen of the United States, residing at Kokomo, in the county of Howard and State 5 of Indiana, have invented a new and useful Skirt-Lifter, of which the following is a specification.

This invention relates to a skirt-lifter; and the object of the same is to provide simple 10 and effective means which are concealed under the outer garments and attached to the front and rear portions of the skirt, so that the latter may be elevated equally all around, and thus quickly convert a long skirt into a 15 short or rainy-day skirt, which operation is easily controlled by the wearer without requiring any of the garments to be loosened or opened, the skirt remaining elevated after the adjustment is made without attention or 20 the least holding by the wearer.

The invention consists in the construction and arrangement of the several parts, which will be more fully hereinafter described and claimed.

25 In the drawings, Figure 1 is a perspective view of a figure showing the method of elevating a skirt from the exterior by means of the improved skirt-lifter. Fig. 2 is a plan view of a separable girth or band adapted to 30 be worn around the waist similar to a belt and under the skirt and having thereon and in connection therewith the improved skirt-lifter devices. Fig. 3 is an elevation of a 35 corset, showing the improved device applied thereto. Fig. 4 is a plan view of a belt which may form an attached part of the skirt and also embody the features of the invention.

Similar numerals of reference are employed 40 to indicate corresponding parts in the several views.

The numeral 1, Fig. 2, designates a girth or band formed of two separable sections 2 and 3, having one set of terminals connected by hooks and eyes 4 and the other set of terminals provided with buttons and button-holes 5 and 6. It will be understood, however, that both sets of terminals may be provided with the same kind of separable fastenings. This girth or band is worn inside 45 of the skirt at about the waist-line and depends partially over the hips. Adjacent to the lower edge of each section, on the outer

side of the said girth or band; a series of three 55 pulleys or sheaves 7 are applied, and leading upwardly therefrom are resilient coiled-wire tubes 8, one from each pulley, the said tubes being secured in such manner as to always have a positive position on the girth or band. The several tubes on each section are converged toward the upper edge of each section 60 and project above said edge or have a short length of the same projected beyond the securing means nearest the upper terminals of the same. By the use of coiled wire in the formation of the tubes they are held open regularly throughout their full length, and they are also rendered resilient to conform with the change of shape or position when the girth is applied without crushing the same. Movably extending through the said tubes and 65 engaging the pulleys or sheaves 7 are cords, wires, or the like, as at 9, the latter devices forming pulling means and which extend above the upper terminals of the tubes and connected to each other and provided with a 70 terminal loop 10 for simultaneously operating the same, or the upper ends of said pulling means may be secured to a tassel, button, or other device. The several pulling devices may extend below the lower edges of the girth- 75 sections any suitable distance, the length of the same being regulated by the length of the skirt, and at their lower ends said pulling devices will be provided with loops 11 to catch over buttons, hooks, or other devices secured 80 at proper intervals and at a suitable elevation on the inner side of the skirt. Instead of using loops at the lower ends of the pulling devices hooks of ordinary form or clasps may 85 be obviously substituted, and this change 90 will be governed by the desire of the user.

In Fig. 3 the improved device is shown applied to a corset, all the parts being the same as those heretofore described and similarly numbered. It will be seen in this instance 95 that the upper ends of the tubes project above the highest securing means therefor, as in the girth construction.

In Fig. 4 a band or waist-belt is shown having the improved skirt-lifting mechanism 100 thereon in the same construction as that heretofore set forth, the tubes being converged inwardly or all concentrated toward a central point instead of in an outward direction, as

shown by Fig. 2. This does not modify the device in the least and simply indicates that the device can be arranged to have the pulling means actuated from a central point or 5 at opposite sides. The device shown by Fig. 4 has the terminals thereof secured by separable fastening means, which may be either hooks and eyes, as shown, or other suitable fasteners.

- 10 In all the forms shown the pulling devices or means running loosely through the tubes will be so disposed that the skirt will be engaged thereby at the front, back, and at the sides, so that an equal pulling tension will 15 be exerted on all portions of the skirt to equally elevate the same throughout its entire circumference. By having the upper terminals of the tubes projected above the upper fastening means therefor, as shown in 20 all the forms of application, a tendency toward abrading wear on the pulling means 9 by the said upper fastening means or the adjacent edge of the girth or band and also a bind of the said means at said portions of 25 the tubes will be prevented.

The improved device as an entirety will work very easily and reliably and can be readily applied in operative position without mutilating the skirt or requiring any change 30 in the construction of the latter. The device as illustrated by Fig. 4 is particularly intended to be made a part of the skirt, so that it will be unnecessary to detach the lifting devices from the skirt when removing the 35 latter from the person.

Many other changes will suggest themselves; but it will be understood that the general application indicated by the several devices shown will convey the idea that all such changes within the scope of the invention are fully contemplated. The number of 40 cords and pulleys may be increased, if desired, and it will be seen also that the skirt can be lifted at one side or at the back without lifting the entire skirt. 45

Having thus described the invention, what is claimed as new is—

1. A skirt-elevator comprising supporting means, series of resilient tubes arranged thereon and converged toward their upper terminals, lower series of pulleys, and pulling devices freely movable through the said tubes and engaging the pulleys. 50
2. A skirt-elevator comprising supporting means, series of resilient tubes arranged 55 thereon and converged toward their upper terminals, securing devices engaging the upper portions of the tubes slightly below the upper ends thereof to prevent abrading wear and binding on the pulling means disposed 60 in said tubes, and pulling means freely movable through the said tubes.

In testimony that I claim the foregoing as my own I have hereto affixed my signature in the presence of two witnesses.

ELIZABETH M. FOREHAND.
